UNITED STATES PATENT OFFICE.

EDWARD SAMUEL, OF PHILADELPHIA, PENNSYLVANIA.

CONDUIT FOR TRACTION-ROPE RAILWAYS.

SPECIFICATION forming part of Letters Patent No. 281,562, dated July 17, 1883.

Application filed May 11, 1883. (No model.)

To all whom it may concern:

Be it known that I, EDWARD SAMUEL, a citizen of the United States, and a resident of Philadelphia, Pennsylvania, have invented 5 certain Improvements in Conduits for Traction-Rope Railways, of which the following is a specification.

My invention consists of certain improvements, fully described hereinafter, in the construction of underground conduits for traction-rope railways.

In the accompanying drawings, Figure 1 is a transverse vertical section of my improved conduit; Fig. 2, a transverse section of the 15 trough with modified form of support for the same; Fig. 3, a section showing a modification of the upper portion of the conduit; and Fig. 4, a perspective view, showing portions of two adjoining sections of the trough.

20 My improved conduit is composed of the trough A, made in sections and provided with flanges a a, the detachable and adjustable bars W W', also made in sections, and the supports D, secured to the trough at suitable intervals, 25 and bearing on appropriate foundations made in the bottom of the trench formed in the ground for the reception of the conduit. The sections of the trough are made of plate-iron or plate-steel, each section being made in one 30 piece by bending or rolling, or both.

While it is not necessary to adhere to the precise shape shown of the trough, I prefer to make it with a rounded base and with opposite parallel sides, b b, terminating in the aforesaid 35 flanges a a. The trough thus made of plate-iron or plate-steel in sections of suitable length is more economical than a cast-iron trough, inasmuch as it is very much lighter and can be made with facility by properly-constructed 40 bending and rolling-mill appliances. The trough, however, demands the use of suitable supports, D, at intervals. These may be made of wrought-iron bars, as shown in Fig. 1, the bars being welded, riveted, or bolted together 45 and secured to the trough; or each support may be made of cast-iron, as shown in Fig. 2; or the supports may be composed partly of wrought and partly of cast iron, constructed in any manner which the judgment of those expert in such matters may suggest, for, while it 50 pert in such matters may suggest, for, while it is essential that the plate iron or steel trough

should be combined with suitable supports, my invention is not restricted to any specific mode of constructing the latter.

There should be supports at the junctions of 55 the sections, as shown in the perspective view, Fig. 4, one support being common to two adjoining sections, thereby serving to maintain them in line; and these supports should have braces w, extending to the flanges of the trough, 60 while the intermediate supports may or may not have these extended braces.

The plates or bars W W' are made in sections, preferably of the same length as the sections of the trough, and may be arranged to 65 break joints with the latter. Provision should also be made for the lateral adjustment of the bars W W' on the trough and for the detachability of one or both of the bars, as described in another application which I have filed for 70 a patent.

Each section of each set of bars W W' has a flange, e, at the top, and a flange, f, at its lower edge for attachment to the flanges of the trough; but this attachment should be such as 75 to permit the lateral adjustment of the said bars on the trough.

The bars are so arranged that there shall be a continuous slot, i, between the flanges e e, for the admission of the arm, which extends from 80 the car to the traction-rope within the conduit.

While the bars W W' may be made of cast-iron, I much prefer wrought iron or steel rolled to the desired shape.

The plates may be provided with turned-down flanges for receiving set-screws, the points of which bear against the flanges of the trough, as shown in Fig. 3, and described in my said former application for a patent.

I claim as my invention—

90 A traction-rope conduit in which a series of troughs, A, made of plate iron or steel, are combined with two sets of bars, W W', one or both sets being removable, and with supports D, substantially as set forth.

95 In testimony whereof I have signed my name to this specification in the presence of two subscribing witnesses.

EDWD. SAMUEL.
